UNITED STATES PATENT OFFICE.

KEITH WILLIAMS, OF CHICAGO, ILLINOIS, ASSIGNOR, BY MESNE ASSIGNMENTS, TO
W. H. MINER, INC., A CORPORATION OF DELAWARE.

ANTIFRICTION BEARING.

Application filed December 27, 1921. Serial No. 525,051.

To all whom it may concern:

Be it known that I, KEITH WILLIAMS, a citizen of the United States, residing at Chicago, in the county of Cook and State of Illinois, have invented a certain new and useful Improvement in Antifriction Bearings, of which the following is a full, clear, concise, and exact description, reference being had to the accompanying drawings, forming a part 10 of this specification.

This invention relates to improvements in anti-friction bearings.

In the manufacture, shipping and application of anti-friction bearings, particularly 15 anti-friction bearings employed as side bearings on railway cars, it is highly essential that the entire device be shipped completely assembled without possibility of any of the parts becoming lost or disarranged either accidentally or from deliberate tampering. Many expedients have heretofore been suggested for permanently retaining the parts 20 of side bearings in assembled relation, but many of the same have not proved entirely satisfactory due to either the expense of applying such retaining means or the difficulty 25 in always applying the same properly, due to the variations which necessarily occur in the manufacture of the parts, most of which 30 are in the form of castings.

The object of my invention is to provide a simple, effective and relatively inexpensive 35 means for retaining the parts of an anti-friction bearing in assembled relation and more particularly as applied to a side bearing 40 for railway cars.

In the drawing forming a part of this 45 specification, Figure 1 is a vertical sectional view taken parallel to the length of a car through the ends of the body and truck bolsters and showing my improvements in connection therewith. And Fig. 2 is a vertical sectional view corresponding substantially to the broken section line 2-2 of Figure 1.

In said drawing, 10 indicates the under 50 side of a body bolster of a car and 11 the upper side of an opposed truck bolster. In the instance shown, the improved side bearing is applied to the truck bolster and the same comprises, broadly, a housing, base casting or retaining member designated generally by the reference A; a wear or bearing plate B; a rolling anti-friction element 55 proper C; and special means for retaining

the parts assembled hereinafter specifically described.

The retaining member or base casting A, as shown, is formed with a bottom wall 12, vertically extending spaced side walls 60 13-13, vertically extending end walls 14-14, reenforcing and limiting ribs 15-15 on the interior of the casting at the ends thereof, and corner lugs or ears 16-16 by which the casting is adapted to be riveted or 65 otherwise rigidly secured to the truck bolster.

On its interior, the base casting A, in the bottom thereof, is preferably provided with a pair of upstanding knobs or teeth 17-17, 70 which extend through correspondingly located openings or perforations 18-18 in the preferably hardened wear plate B. The thickness of the wear plate B is less than the height of the teeth 17, so that portions of 75 the latter project upwardly and are adapted to engage in corresponding openings 19-19 provided in the bottom of the anti-friction element C to thereby prevent the latter from being shifted bodily with respect to the base 80 casting A.

The anti-friction element proper C, in the form shown, is of the rolling rocker gravity self-centering type and is preferably formed with top and bottom concentric bearing surfaces 20 and 21, the latter being of longer radius than the former. Said top and bottom bearing surfaces 20 and 21 are merged with arcuate side surfaces 22-22. With the arrangement shown, it is evident that, 90 when the element C is shifted to either side of its normal central position shown in Figure 1, the center of mass is elevated and consequently the element will automatically return to central position upon removal of the 95 actuating force.

To retain the anti-friction element C in assembled relation with the base casting A, I have provided the following means. The anti-friction element C is initially formed 100 or cast with an opening 23 extending axially therethrough, within which is inserted a pin D, the latter being of such length that its ends project beyond the ends of the anti-friction element C and within arcuate elongated openings 24-24 provided in the side walls 13 of the base casting A. The vertical height or width of the openings 24 is made appreciably greater than the diameter 105 of the pin D. The latter is provided at one 110

end with an integral head 125 and at its opposite end is made of reduced diameter, as indicated at 26. Applied to the reduced end 26, is a bushing 25, the latter preferably consisting of a short section of pipe of such diameter that it may be applied with a driving fit. The length of said bushing is also such that the end of the pin D will extend slightly beyond the outer edge of the bushing, so that said extreme end of the pin may be peened or riveted over the bushing, as indicated at 126. The pin D is inserted in place after the anti-friction element C has been placed within the base casting and the bushing 25 thereafter applied. With the features shown and described, it is evident that the anti-friction element C cannot be removed from the base casting without the use of special tools and the destruction or mutilation of some of the parts, and the anti-friction element C will, in turn, retain the bearing plate B in its proper position.

I claim:

1. In an anti-friction bearing, the combination with a retaining member provided with spaced integral side walls and having a longitudinally extending bearing surface; of an anti-friction element adapted to have rolling contact with said bearing surface and located between said side walls; and means for retaining said element in assembled relation with said retaining member, comprising a pin headed at one end and extending through the anti-friction element and having its ends projecting beyond the ends of the anti-friction element, a bushing on the other extended end of said pin rigidly and permanently attached thereto, the side walls of the retaining member having elongated openings therethrough within which said

ends of the pin are adapted to work back and forth, all the portions of said bushing, of the headed end of the pin and of the pin lying between the outer planes of the side walls of said retaining member, being of 45 smaller diameter than the width of said openings.

2. In an anti-friction bearing, the combination with a retaining member having spaced, integrally formed side walls each 50 with an elongated slot therein; of an anti-friction element disposed within said retaining member between said side walls and adapted for rolling movement, said element having a bore extended therethrough; and means for positively retaining said element and member in assembled relation comprising: a pin extending through said bore of said element and elongated sufficiently for its ends to project beyond each end of said 60 element and within the respective slots of the side walls; and means on each said extended end of said pin rigid and associated with said pin, each of said means being of larger diameter than the bore of said element whereby to prevent axial removal of said pin from said element, the means on at least one end of said pin being applicable to the pin after the pin has been inserted through said element and of such character 70 that removal thereof is impossible without destructive effect after the parts have been assembled.

In witness that I claim the foregoing I have hereunto subscribed my name this 9th 75 day of Dec., 1921.

KEITH WILLIAMS.
